UNITED STATES PATENT OFFICE.

CHARLES JOHNSON NOGLE AND GEORGE HAAS, OF GALVESTON, TEXAS.

RAIL FASTENING OR CHAIR

No. 910,411.

Specification of Letters Patent.

Patented Jan. 19, 1909.

Application filed July 8, 1907. Serial No. 382,801.

To all whom it may concern:

Be it known that we, CHARLES JOHNSON NOGLE and GEORGE HAAS, citizens of the United States, residing at Galveston, in the county of Galveston and State of Texas, have invented certain new and useful Improvements in Rail Fastenings or Chairs, of which the following is a specification.

Our invention relates to new and useful improvements in rail fastenings.

The object of the invention is to provide a simple and positive fastening which not only acts to hold the rails in place, but prevents spreading or tilting of the same.

Another feature resides in the provision of broad and flat bearings alternately applied from opposite sides of the rails, the said bearings being disposed to cause the rails to incline slightly inward.

Finally the object of the invention is to provide a device of the character described that will be strong, durable, efficient and simple and comparatively inexpensive to construct, also one in which the several parts will not be likely to get out of working order.

With the above and other objects in view, the invention has particular relation to certain new and useful features of construction, a preferable embodiment of which is described in the following specification and illustrated in the accompanying drawings, wherein:

Figure 1 is a perspective view of a portion of a track showing the fastening applied thereto. Fig. 2 is an end elevation of one of the rails and a portion of the ties showing the fastenings in place. Fig. 3 is a perspective view of the inner fastening member, and Fig. 4 is a perspective view of the outer fastening member.

In the drawings, the numerals 1 and 2 designate the usual ties and 3 the rails.

In carrying out the invention, inner members 4 and outer members 5 are provided. Each member is formed with upwardly inclined clamps or hooks 6 which snugly engage over the flange of the rail as clearly shown in Fig. 2. These hooks project from a plate 7 having a flat underside 8. It will be observed that the plates are flat and broad to give a substantial bearing on the ties on

which they rest, thus bracing them against tilting.

The inner member 4 is applied with its hook toward the inside of the track. Attention is directed to the upper side of the plate 7 of the inner member which is inclined downward toward the inside of the track or inward, as indicated at 9. The outer edge is beveled at 10 to permit an easy application of the rail and allow the same to be readily slid onto the plate. A sharp edge would interfere, as is evident.

The outer member 5 is disposed with its hook outward, while the upper surface 11 of its plate, 7 inclines inward and downward, lying in the same plane as the surface 9. This causes the rail 3, as indicated in Fig. 2 to incline slightly inward, thus affording a better track and in co-operation with the flat bearing of the plates, resisting spreading and tilting which results in safety and strength.

The inclined surfaces and the hooks conform to the contour of the flange of the rails, so that a pocket snugly receiving the same is formed, while spikes 12 driven through suitable openings 14 in the members pass in close proximity to the flange into the ties, thereby firmly holding the members and rails in place.

In laying the track, the inner members 4 are placed on the tie 1 as described and shown in Fig. 1, that is, near each end of the tie. The rails 3 are next placed on the members and being properly gaged, are spiked in place. The outer members are disposed on the next tie 2, with their hooks reversed, and owing to their inclined surface are readily driven into position and spiked down. The members are arranged in this alternating and staggered relation throughout the track, so that the rails are rigidly clamped by alternating flange engaging hooks on each side of their webs.

What we claim is:

In a rail fastening, the combination with the rail and the ties, of separate fastening members, one of said members placed on one tie and the other on another tie, one of said members comprising an inclined plate provided with a rail receiving hook at its upper end, the other member comprising an in-

clined plate provided with a rail receiving hook at its lower end, said plates being spiked on separate ties with their lower ends directed inward, the hook of one plate being on the outside of the rail and the hook of the other plate being on the inside of the rail.

5 In testimony whereof we have signed our

names to this specification in the presence of two subscribing witnesses.

CHARLES JOHNSON NOGLE.

GEORGE HAAS.
